UNITED STATES PATENT OFFICE.

FRANK FONTANA, OF SAN FRANCISCO, CALIFORNIA.

DESIGN FOR A STREET-CLOCK.

51,280.

Specification for Design. Patented Sept. 18, 1917.

Application filed August 1, 1917. Serial No. 183,992. Term of patent 7 years.

To all whom it may concern:

Be it known that I, FRANK FONTANA, a subject of the King of Italy, and a resident of the city and county of San Francisco, State of California, have invented a new, original, and ornamental Design for a Street-Clock, of which the following is a specification, reference being had to the accompanying drawing, forming part thereof.

Figure 1 is a front elevation of a street clock illustrating my new design.

Fig. 2 is a plan view of the street clock.
I claim:

The ornamental design for a street clock substantially as shown.

FRANK FONTANA.
